United States Patent

Des. 239,456

Patented Apr. 6, 1976

239,456

TOY BEAR

William J. Maloney II, East Aurora, N.Y., assignor to
The Quaker Oats Company, Chicago, Ill.

Filed Dec. 18, 1973, Ser. No. 425,705

Term of patent 14 years

Int. Cl. D21—01

U.S. Cl. D34—15 B

FIG. 1

FIG. 2

FIG. 3

FIG. 1 is a front elevational view of a toy bear showing my new design;

FIG. 2 is a rear elevational view thereof; and
FIG. 3 is a side elevational view thereof.

I claim:

The ornamental design for a toy bear, substantially as shown.
